UNITED STATES PATENT OFFICE

109,648

DESIGN FOR A TELEPHONE CABINET

Theodore N. Saaty, Providence, R. I., assignor
to The Screw Machine Products Corporation,
a corporation of Rhode Island

Application April 29, 1937, Serial No. 69,052

Term of patent 14 years

To all whom it may concern:

Be it known that I, Theodore N. Saaty, a citizen of the United States, residing at Providence, in the county of Providence and State of Rhode Island, have invented a new, original, and ornamental Design for a Telephone Cabinet, of which the following is a specification, reference being had to the accompanying drawing, forming a part thereof,

Fig. 1 is a perspective view; and Fig. 2 is a section of the front wall of a telephone cabinet.

I claim:

The ornamental design for a telephone cabinet substantially as shown.

THEODORE N. SAATY.
